UNITED STATES PATENT OFFICE

EDWARD J. ALBERT, OF PHILADELPHIA, PENNSYLVANIA, ASSIGNOR TO THWING INSTRUMENT COMPANY, OF PHILADELPHIA, PENNSYLVANIA, A CORPORATION OF PENNSYLVANIA

DRIVING MECHANISM FOR RECORDING APPARATUS

Application filed November 20, 1926. Serial No. 149,783.

My invention relates to driving mechanism for recording apparatus, and it has for one object the provision of means whereby the tendency for the material to creep on a recording roll may be substantially overcome.

Another object of my invention is to provide a construction, wherein the supply and rewinding rolls are operated by power from the recording roll transmitted by the material to be marked. One advantageous result of thus causing the material to serve as a linkage between the several rolls is the elimination of a second driving shaft heretofore considered essential and the consequent simplicity in the supporting structure as a whole.

My invention further consists in the details of construction and operation and arrangement, hereinafter described and claimed and illustrated in the accompanying drawings, wherein

Figs. 1, 2 and 3 are side, front and top plan views, respectively, of a structure embodying my invention;

Fig. 4 is an enlarged detail, side elevational view of the supply and rewinding rolls; and

Fig. 5 is a detail, vertical, enlarged sectional view of the rewinding roll, the sectional plane being taken on the line V—V of

Fig. 4.

The apparatus shown in the drawings comprises broadly a supply roll 1, having a desired material 2, say paper, that extends therefrom upwardly around a recording roll 3 and then downwardly to a rewinding or take-up roll 4, the paper 2 being held against the recording roll 3 by pressure applied on a central element only by means of a friction ribbon contact roll 5. The several rolls may be supported by means of a structure 6.

Considering the supply roll 1 in greater detail, an inner tube 7 thereof is supported on conical end plugs 8 and 9 which are respectively provided with end flanges 11 and 12 positioned to abut against the adjacent ends of the tube 7. The end plugs 8 and 9 are respectively mounted on end portions 13 and 14 of a shaft 15, as particularly illustrated in Fig. 2. The flanges 11 and 12 may be rigidly clamped in abutting relation to the ends of the inner tube 7 by means of a nut 16 which

engages a threaded portion 17 of the shaft 15 adjacent to the end portion 14.

The shaft end portions 13 and 14 terminate in bearing portions 18 and 19 which respectively engage apertures 21, 21 formed in an upper end 22 of a pair of bracket members 23 and 24. The bracket members 23 and 24 are respectively secured to inner sides 25 and 26 of a pair of upright side plates 27 and 28 of the main supporting structure 6. The apertures 21 may be provided with angled entrance slots 29 permitting the insertion or removal of the bearing portions 18 and 19 and, consequently, the supply roll 1 as a whole, from a front side 31 of the supporting structure 6.

As shown in Fig. 5, the rewinding roll 4 comprises a supporting tube 32, opposite ends of which are supported on members 33 mounted on a shaft 34. The opposite ends of the shaft 34 respectively extend into apertures 35, 35 positioned at a lower end 36 of the brackets 23 and 24, as in the case of the shaft 15. The apertures 35 are provided with angled access slots 37, so that the rewinding roll 4 may be removed from the front side 31 of the structure 6 as in the case of the supply roll 1.

One end of the end members 33 is provided with a hub portion 38 constituting a support for a loosely mounted sleeve 39. A lower gear-wheel 41 is rigidly secured to the sleeve 39 and meshes with an upper gear-wheel 42 mounted on the end plug 8 of the supply roll 1. The sleeve 39 is provided with a groove 43, Fig. 5, whereby an intermediate portion 44 of a wire 45 may engage a circular recess in the hub portion 38. The ends of the wire 45 are clamped by screws 46 on the lower gear-wheel 41 in such manner that the intermediate portion 44 is forced into resilient frictional engagement with the hub 38. The engagement is such that slippage occurs when the force exerted by the lower gear-wheel 41 on the rewinding roll 4 exceeds a predetermined value. Such increase in force results from the fact that the diameters of the supply and rewinding rolls 1 and 4 are constantly changing, the former decreasing and the latter increasing.

The recording or printing roll 3 provides a support for the paper 2 passing over the same, as shown in Fig. 1 of the drawings, and it may be mounted on a shaft 47, end portions 48 and 49 of which are respectively journaled in the side members 27 and 28 of the supporting frame 6. The shaft end portion 47 may be connected by reduction gearing 50 to a clock or other source of power 51, whereby the recording roll 3 may be positively driven.

Heretofore, various methods involving pins and the like have been employed to prevent axial displacement of the paper 2 on the recording roll 3. Such displacement may result, for example, from the fact that the diameter of the roll 3 varies for different elements along the length thereof. The tendency for the paper to creep on the roll 3 is overcome in my invention by the provision of the friction driven pressure roll 5 which is so formed as to have a substantially point contact with one element only of the roll 3. Such contact may be afforded by oppositely beveling side portions 52 and 53 of the roll 5, so that a meeting edge 54 of these portions represents a single element, the plane of which is common with that of a single element of the recording roll 3.

Sufficient pressure may be established between the edge 54 of the roll 5 and the portion of the paper 2 in contact with the wheel 3 by rigidly mounting the wheel 5 on a spring wire 55, opposite ends 56 and 57 of which are rotatably supported in the side plates 27 and 28 respectively. Axial displacement of the wire 55 may be prevented by shoulders 58 which abut against the side plates 27 and 28. Thus, the paper 2 is held against the recording roll 3 by pressure applied upon substantially one element only of the roll 3 which element is of constant diameter.

The roll 5 is preferably positioned so that the element thereof represented by the edge 54 engages a substantially central element of the roll 3, inasmuch as such transverse or axial expansion of the paper 2 as occurs is equally divided on both sides of the center. Hence, the maximum error caused by change in width with varying humidity is only one-half as great as would occur if the paper were rigidly held at one end. It is also noted that the center of the paper 2 is most frequently used.

Assuming a recording pen 59 in operative relation to the portion of the paper 2 passing over the roll 3 and the latter driven by the clock 51, the edge 54 of the pressure roll 5 is held in resilient frictional engagement with the paper 2 by the spring wire 55, causing the paper 2 to be forced against the recording roll 3 with a pressure that is applied on substantially one element only of said roll 3. As a result of the frictional engagement thus established between the paper 2 and the

recording roll 3, a movement of the paper 2 occurs in the direction indicated by the arrows of Fig. 1. The continued movement of the paper 2 causes the unwinding of the supply roll 1 and the rewinding of the paper 2 after it has passed over the recording roll 3 by the roll 4. As above noted, the power necessary to operate the supply and rewinding rolls 1 and 4, respectively, is transmitted from the recording roll 3 through the paper 2 which forms a linkage therebetween. Hence, one driving shaft only is required instead of two as has heretofore been the practice. When it is necessary to replace either of the rolls 1 or 4, it is necessary only to lift the same forwardly and upwardly toward the front side 31 of the supporting structure 6.

While I have shown only one form of embodiment of my invention, for the purpose of describing the same and illustrating its principles of construction and operation, it is apparent that various changes and modifications may be made therein, without departing from the spirit of my invention, and I desire, therefore, that only such limitations shall be imposed thereon as are indicated in the appended claim or as are demanded by the prior art.

I claim:

In a recording instrument, in combination, a pair of co-acting rolls having a desired material interposed therebetween, at least one of said rolls being so formed as to have substantially a point contact with one element of the other roll to prevent displacement of the interposed material axially of the roll, and a spring wire for supporting one of said rolls to establish the necessary pressure between the rolls.

EDWARD J. ALBERT.
